UNITED STATES PATENT OFFICE.

CHARLES E. BELL, OF HILLSBORO, OHIO, ASSIGNOR TO THE C. S. BELL CO., OF HILLSBORO, OHIO, A CORPORATION OF OHIO.

GRINDING-MILL.

1,009,887.

Specification of Letters Patent. Patented Nov. 28, 1911.

Application filed October 12, 1909. Serial No. 522,305.

To all whom it may concern:

Be it known that I, CHARLES E. BELL, of Hillsboro, in the county of Highland and State of Ohio, have invented certain new and useful Improvements in Grinding-Mills; and I hereby declare that the following is a full, clear, and exact description thereof, reference being had to the accompanying drawings, which form part of this specification.

This invention is an improvement in mills for grinding corn and cobs for feed.

The object of the invention is to produce a mill of this kind which shall be extremely simple in construction, very substantial, durable, and efficient in operation.

One of the objects of the invention is to enable the stationary bur to be readily adjusted to perfect alinement with the revolving bur, and easily kept in alinement at all times. It will not be necessary to adjust the bur often, but it is highly desirable and necessary that means be provided for adjusting the stationary bur to compensate for any wear in the bearings of the main shaft, which would affect the axial position of the revolving bur. This and other novel features of the invention will be explained in connection with the drawings; and the invention consists in the novel construction and combination of parts of the mill as illustrated in the drawings and hereinafter described and summarized in the claim.

In the accompanying drawings—Figure 1 is a side elevation of the complete mill. Fig. 2 is an enlarged plan view of same with the hopper and housing removed; Fig. 3 is an enlarged vertical longitudinal section on line 3—3, of Fig. 2. Fig. 4 is a transverse sectional view on line 4—4, of Fig. 3; Fig. 5 is an end view of the machine with drive pulley removed. Fig. 6 is a detail plan view showing the horizontal adjusting device for stationary bur; and Fig. 7 is a detail sectional view on line 7—7, of Fig. 6.

The mill comprises a casting or frame 1 which is approximately provided at each end with flattened portions 1^a upon which the shaft journal bearings 2, 2^a, are mounted. 50 and at the sides of portions 1^a, are integral depending pieces 1^b to which the upper ends of the legs 3 are attached. These legs are preferably of wood bars, and are secured to the parts 1^b of the frame by means of bolts 55 3^a transfixing the parts 1^b, and the upper

ends of the legs, washers 3^b being placed between the heads of the bolt and the outer sides of the legs as shown. The legs 3 may also be provided at bottom with angle-irons 3^c which are bolted thereto, and can also be bolted to the floor upon which the mill is placed, so as to hold the mill securely in position.

The bearing 2 is secured to the casting 1 by bolts 2^b and the bearing 2^a is secured thereto by bolts 2^c. The main shaft 4 is journaled in said bearings, and extends through bearing 2 and into bearing 2^a. The shaft has an end thrust against a block 2^e in bearing 2^a; said block being longitudinally adjustable in bearing 2^a by means of a screw 2^f operable by a hand-piece 2^g, and screw 2^f can be locked when adjusted, by means of a hand-nut 2^h. Ball bearings of any suitable construction, indicated at 2ⁱ, 75 may be interposed between the block 2^e and the shaft 4 to receive and transmit the end thrust of the shaft 4.

On the shaft 4 adjacent journal 2^a is keyed a disk 5 to the face of which is bolted an 80 annular revolving bur 5^a; opposite bur 5^a and coacting therewith is an annular bur 5^b, which is bolted to an annular support 5^c, which is provided at diametrically opposite sides with trunnions 5^d that respectively engage holes in plates 5^e mounted upon lateral flanges 1^g on the sides of frame 1. Each plate 5^e is rigidly secured in position on flange 1^g by means of a through-bolt 5^f. (see Fig. 7) which engages a slot in the flange 1^g so that the plate can be adjusted longitudinally of the shaft 4; this adjustment is regulated by means of an eccentric stop 5^g which is fastened by a bolt 5^h to the flange 1^g. By loosening bolts 5^g and 5^h the eccentric 5^g can be turned on bolt 5^h so as to arrest plate 5^e in the exact position to which it should be adjusted. It will be seen that the fixed bur 5^b is mounted on the adjustable support 5^c, and the latter can be adjusted at either side so as to bring the face of the fixed bur 5^b exactly parallel with the face of the rotary bur 5^a. The trunnions upon which the support 5^c is mounted enable it to adjust itself automatically, in a vertical direction, relatively to the bur 5^b; and, by having plates 5^e adjustable, support 5^c can be adjusted in a horizontal direction, and these vertical and horizontal adjustments 100 permit obtaining absolute parallelism be-

105 110

tween the faces of the fixed and rotating burs. This arrangement provides for a double or universal adjustment of the stationary bur so that at any time the plane 5 of the face of the revolving bur is changed, the plane of the face of the stationary bur may be easily adjusted to suit. One of the trunnions 5^a of the support 5^c, may be held in a fixed position, as it is only necessary to 10 adjust one side of such support to bring the rotary bur face parallel with that of the revolving bur. This is readily done at trunnion 5^a by loosening the bolts and turning the eccentric 5^c, and then fastening the bolts. 15 The frame casting 1 is also provided with a semi-annual depending portion 1^a inclosing the lower portion of the burs, and having a discharge spout 1^c. The upper portions of the burs are covered by semi-annual 20 housing 1^b attached to the lower portion 1^a by bolts 1^a transfixing perforated lugs on the frame 1, and housing 1^b, as shown.

On the shaft 4 are placed a series of 25 breaker castings 4^b which are in the form of rings strung on shaft 4 and provided with projecting teeth 4^c adapted to coöperate with diagonal ribs 6^b in the underlying shell 6 attached to the frame 1. The rings 4^b are 30 cast with interlocking projections and recesses as shown at 4^c, and the outermost of the rings may be fastened to the shaft by means of through-bolts 4^d or in other suitable manner, so that all must rotate together. 35 The shaft 4 may be driven by a pulley 4^p on its outer end, as shown.

The lower portion of the grinding casing is formed of a curved metal grinding shell 6 which is hinged at one side to the frame 40 1 as at 6^a, and is detachably connected at its opposite side to the frame 1 by means of lugs 6^a adapted to embrace a corresponding lug 1^r on the frame 1; said lugs when the shell 6 is in closed position being transfixed 45 by a wooden break-pin 6^b; and in case any hard substance goes into the mill the pin will break and allow the grinding shell 6 to drop without breaking the working parts. After such substance is removed the grinding shell 6 may be closed and secured in position by a new pin.

A hopper 7 is fitted over the breakers 4 and supported on the frame 1 as shown; being fastened to the frame by means of bent 55 rods 7^a attached to the hopper at one end and having their free ends threaded and projecting through eyes 1^r on the side of frame 1 and secured by nuts as shown. This enables the hopper to be readily detached 60 when desired.

The degree of fineness to which the material is ground may be regulated by a slide 8

adjustably fitted between the breakers 4^c and the stationary bur, as indicated in the drawings; said plate 8 may be secured when 65 adjusted by means of a thumb-nut 8^a on a bolt 8^b attached to frame 1 and transfixing a slot in the plate 8.

The material to be ground, such as corn on the cob, is placed in the hopper, and will 70 be quickly broken into small pieces by the breakers 4^c co-acting with the ribs on shell 6; the breaker teeth are so arranged on the shaft that they will feed the crushed material toward the burs; and the necessary degree of fineness of the crushed material before it can pass to the burs is regulable by the plate 8. The crushed material passes from the shell to and between the burs, and is reduced by the latter to a meal; the fineness of the meal depending upon the relative adjustment of the burs 5^a, 5^b. 75

By this mill varieties of feeds can be ground; and one adjustment of the stationary bur plate enables it to be kept in alignment with the revolving bur at all times. The mills when erected are properly adjusted so that the burs are parallel and they require very little attention thereafter until the journals of the shaft wear. 85

The feed regulating plate 8 simply cuts off the amount of material that passes from the stationary bur and can be adjusted to vary the amount of product passing to the bur from the hopper. The teeth on the rings 95 tend to feed the material forward toward the burs; when the mill is running empty the burs are kept out of actual contact by means of a spring washer 4^e strung on the shaft between the rearmost breaker casting 100 4^b and the rear end of the casing, see Fig. 3. This prevents wearing out of the burs when material is being ground.

Having described my invention what I claim as new and desire to secure by Letters 105 Patent thereon is:

In a grinding mill the combination of a frame, an endwise adjustable rotary shaft journaled therein, a rotary bur fixedly mounted on said shaft, a bur support adjacent the rotary bur and provided with trunnions, a bur on said support, plates engaging said trunnions, one of said plates being adjustable longitudinally of the shaft, an adjustable eccentric stop engaging the end 110 of said plate, and bolts for fastening the eccentric and plate when adjusted.

In testimony that I claim the foregoing as my own, I affix my signature in presence of two witnesses.

CHARLES E. BELL.
